[57] ABSTRACT

The invention is a cap for a "pill bottle" consisting of upper and lower members forming a discharge passage therein and therebetween, discharge being possible only upon certain unanticipatable manipulations of the cap.

FIG.6

CONTAINER CAP WITH TRAP DISPENSING MEANS

OBJECTS OF THE INVENTION

It is amongst the primary objects of this invention to provide a tamper proof cap for a "pill bottle" or the like which deters access to its contents to the unknowing and the re-use of the container.

THE DRAWING

FIG. 1 is a sectional view showing a cap in accordance with the invention mounted on a container;

FIG. 2 is an exploded view of the cap in side elevation;

FIG. 3 is a sectional view of the lower member of the cap;

FIG. 4 is a sectional view of the upper member of the cap of FIG. 1;

FIG. 5 is a sectional view of the lower member of another embodiment of cap; and

FIG. 6 is a sectional view of the upper member of the cap of FIG. 5.

DESCRIPTION OF THE INVENTION

A cap 10 in accordance with the invention is shown mounted on container 12 in FIG. 1. The cap consists of upper and lower members 14 and 16 as shown in FIG. 2.

The lower member is directly mounted on the container and is provided with bead 18 adapted to fit into a slot (not shown) formed in the neck of the container to hold the lower member in fixed position with respect to the container.

A portion of lower member 16 is set back from its remainder to form an edge 20 by means of which the cap can seat on the lip of the container. Thus member 16 extends interiorly and exteriorly of the bottle for reasons hereinafter appearing. In lieu of this set back, member 16 need merely be provided with a seating ring while remaining otherwise of uniform diameter.

Bottom wall 22 of lower member 16 is exteriorly inclined to form a chute. When the container is turned upside down, "pills" are moved by gravity along the inclined surface to opening 24 formed in wall 22. A recess 26 formed in upper member 14 corresponds in diameter to that of opening 24 and when recess 26 aligns with opening 24, the interior of the cap is in direct communication with the interior of the container and an item from the container can gain access to the interior of the cap.

If the upper member is thereafter turned in a counter-clockwise direction, recess 26 and content will eventually align with opening 28 formed in the sidewall of member 16. A corresponding opening 30 formed in the sidewall of the upper member provides access to the exterior.

It may be seen that by virtue of this construction a relatively tamper proof cap has been provided, a cap which, amongst other things, cannot be readily "opened" by a child manipulating the cap by chance although a blind person having instructions would have no difficulty in gaining access to the contents of the container.

To extract a pill or other item from the container, the container must be first turned "upside down" so a pill may be directed to opening 24. Either before or after the inversion of the container the cap must be rotated

in a clockwise direction to align opening 24 and recess 26. Once this occurs, the cap must be rotated on a counter clockwise direction to align recess 26 with opening 28, recess 26 and opening 30 being permanently aligned.

Hence, a sequence of three distinct movements of the container is required to extract something from the interior:

1. the inversion of the container
- 10 2. a clockwise movement of the cap, and
3. a counter clockwise movement of the cap.

The odds against this occurring by chance would appear to be remote.

Accurate alignment is insured by the provision of a stop 32 in the lower member. The stop extends into a recess 34 formed in the upper member. Recess 34 is dimensioned so that member 26 aligns with opening 24 when further rotation of the upper member in one direction, is prevented and with opening 28 when further rotation of the upper member is prevented in the opposite direction.

The cap may not be readily removed from the container being held thereon by a locking ring 36. A segmented skirt 38 permits the cap to be readily mounted on the locking ring but not readily removed therefrom.

The cap material is preferably of a flexible plastic and the container as well as the cap may readily be manufactured by injection molding techniques.

The plastic employed should be impact resistant and in the case of the cap, resilient enough to permit expansion of the skirt without fracture during capping. The container could be of clear transparent plastic but all other portions should be opaque so that the operation of the mechanism cannot be observed.

35 A shallow anti-load depression 40 is provided in the lower member to frustrate reloading attempts. If the cap is deliberately manipulated so that access to its interior may be had and a pill introduced therein, the pill would lodge in depression 40 and effectively jam the mechanism, as may be seen in the drawing.

If, by inverting the container, depression 40 is avoided and a pill is actually introduced into the cap, the walls forming opening 24 are angled to deter reentry of a pill into the container although it is this very angling which facilitates the entry of a pill into the cap from the container. In FIGS. 5 and 6 a modification is shown whereby the upper member is spring biased and automatically closes off the discharge system when not in use.

50 In this modification, the lower member is provided with a flexible leaf 42 which when in equilibrium extends across opening 24 to obstruct the same. Leaf 42 is preferably integral with the remainder of lower member 16 and is anchored only at one end so it may be flexed.

55 A slot 44 dimensioned to house the leaf is formed in upper member 14 and when member 16 is turned in a clockwise direction, the leaf bends so as to clear opening 24 and admit an item into the cap. When the leaf is turned in a counter clockwise direction it will move the item to openings 28 and 30 so that the item can be discharged from the cap, the leaf always urging the return of the upper member to its equilibrium position. Once again, the container must be inverted for the operation to be carried off successfully.

60 65 I claim:

1. A container cap comprising a lower partitioning member adapted to plug the mouth of a container and

be held in fixed position with respect therewith; an upper capping member mounted over the plug having a chamber formed in its underside; said capping member being movable around the container mouth; a discharge opening formed in the capping member; a discharge passage formed in the lower partitioning member; the chamber and passage being unobstructedly

alignable upon the movement of the capping member; the chamber and the opening being alignable upon further movement of the capping member; said capping member being spring biased with the spring obstructing the discharge passage in the rest position of the capping member.
